Fig. 5

FIGURE 1 is a drawing showing a side elevational view of my new design for a boat;

FIGURE 2 is a drawing showing a top perspective view thereof;

FIGURE 3 is a drawing showing a rear perspective view thereof;

FIGURE 4 is a drawing showing a front perspective view; and

FIGURE 5 is a drawing showing a bottom view.

The closely spaced parallel transverse lines and chevron-like area immediately adjacent said lines as shown on the bottom rear in FIGURE 5 represent changes in surface texture.

I claim:

The ornamental design for a boat, as shown and described.
